BUBBLE MAKING FIGURE TOY

Norman Austin Greene, New Rochelle, N. Y.

Application November 13, 1957, Serial No. 48,439

Term of patent 14 years

(Cl. D34—2)

Fig. 1.

Fig. 2.

Fig. 3.

Fig. 4.

Fig. 1 is a front elevational view of a bubble making figure toy showing my new design;

Fig. 2 is a similar view, but with the head raised;

Fig. 3 is a side elevational view looking toward the right of Fig. 1; and

Fig. 4 is a rear elevational view.

I claim:

The ornamental design for a bubble making figure toy, substantially as shown.
